(57) **CLAIM**

The ornamental design for a key for a keyboard, as shown and described.

DESCRIPTION

FIG. 1 is a perspective view of a key for a keyboard showing the new design;

FIG. 2 is a top view thereof;

FIG. 3 is a left side view thereof;

FIG. 4 is a right side view thereof;

FIG. 5 is a rear view thereof;

FIG. 6 is a front view thereof; and,

FIG. 7 is a bottom view thereof.

The broken line showing of the bottom of the key in FIG. 7 is for environmental purposes only and forms no part of the claimed design.

1 Claim, 6 Drawing Sheets
